FIG. 1.

FIG. 2.

My design comprises a swim training device characterized by the integral combination of a set of pulley weights within a frame of vertical, spaced tubes; a single flat supporting base extending therefrom having a flat inclined table angularly supported on said single base by two spaced tubular members which harmonize with the spaced vertical tubes of the frame, all as shown.

I claim:

The ornamental design for a swim training device, as shown and described.
